UNITED STATES PATENT OFFICE.

FRANK W. CALVERT, OF NARBERTH, PENNSYLVANIA, ASSIGNOR TO THE CHARLES E. HIRES COMPANY, OF PHILADELPHIA, PENNSYLVANIA, A CORPORATION OF PENNSYLVANIA.

DESIGN FOR AN ICE-CHEST FOR LIQUID-DISPENSING APPARATUS.

42,268.

Specification for Design.

Patented Mar. 12, 1912.

Application filed August 19, 1908. Serial No. 449,387. Term of patent 14 years.

To all whom it may concern:

Be it known that I, FRANK W. CALVERT, a citizen of the United States, and a resident of Narberth, Montgomery county, Pennsylvania, have invented a certain new, original, and ornamental Design for an Ice-Chest for Liquid-Dispensing Apparatus, of which the following is a specification, reference being had to the accompanying drawing, forming part thereof, which shows a perspective view of the ornamental design for an ice-chest for liquid-dispensing apparatus forming the subject-matter of my invention.

The structure is substantially cylindrical in shape, with a substantially flat top and bottom; the central portion bulging slightly and joining, at top and bottom of the chest, annular ribs or projections which increase

slightly in diameter, those at the top terminating adjacent a horizontal element forming the actual top of the structure. This top is provided with ornamental projections adjacent the margin of the same, with a substantially circular plate in the center having radiating projections, while the base proper is provided with ornamental feet projecting from the lower outwardly extending rib, one of such feet being shown.

I claim:

The ornamental design for an ice chest for liquid dispensing apparatus, as shown and described.

FRANK W. CALVERT.
